UNITED STATES PATENT OFFICE.

WALTER McCAFFERTY, OF BUTTE, MONTANA.

RAILROAD-RAIL.

No. 874,788.

Specification of Letters Patent.

Patented Dec. 24, 1907.

Application filed January 29, 1907. Serial No. 354,653.

To all whom it may concern:

Be it known that I, WALTER McCAFFERTY, a citizen of the United States, residing at Butte, in the county of Silverbow, State of Montana, have invented certain new and useful Improvements in Railroad-Rails; and I do hereby declare the following to be a full, clear, and exact description of the invention, such as will enable others skilled in the art to 10 which it appertains to make and use the same.

This invention relates to railroad rails, and more particularly to that class known as compound rails. The fact that such rails 15 must be formed in such a manner that the sections composing the same will be rigidly and securely held in relative position is readily appreciable, and hence the object of my invention is to produce a rail of this 20 class of such construction that it will satisfy this condition.

Broadly speaking, the rail embodying my invention comprises a pair of sections, namely a base section and a tread section, 25 and the tread section includes a kerfed flange in which a flange, formed upon the base section, is received, the flanges of the two sections being bolted together in this position.

30 In carrying out my invention the opposing sides of the kerf in the flange upon the tread portion are converged upwardly and the flange upon the base portion is also tapered upwardly and is adapted to be snugly received in the kerf, it being understood that the initial passage of a train over the track 35 will serve to wedge the two sections together and to prevent their movement with respect to each other.

40 In the accompanying drawings: Figure 1 is a side elevation of a section of rail constructed in accordance with my invention, Fig. 2 is a detail vertical sectional view taken transversely through the rail before 45 the bolts are applied, and, Fig. 3 is a similar view showing the relation of the rail sections after the bolts are applied.

Referring more specifically to the drawings, the rail is shown as being formed of a

plurality of tread and base sections which 50 are indicated respectively by the numerals 5 and 6.

The tread sections comprise each a tread portion which is of the usual form and a depending integral flange 7 which is kerfed 55 or bifurcated as at 8, the walls of the kerf or bifurcation being converged upwardly as clearly shown in Figs. 2 and 3. Formed integral with the base section 6 is an up- 60 standing flange 9, the side faces of which are converged upwardly so that in reality the flange is a tapered one.

Formed through the flange 9 is an opening 10 and openings 11 are formed through the spaced portions of the flange 7. As shown 65 in Fig. 2 of the drawing these openings only aline when the tread section is in proper position upon the base section and as the flange 9 is very snugly received in the bifurcation or kerf of the flange 7, the tread portion is to 70 be pressed down upon the base portion until the openings 10 and 11 do aline after which bolts 12 are engaged through the openings and serve very effectually to prevent the separation of the sections formed in the rail. 75 Furthermore, the fact that the tread section is so snugly received upon the base section renders it obvious that the bolts 12 will be considerably relieved of strain.

In forming a length of rail from my sections, each tread section is placed directly over the junction of the two base sections, as clearly shown in Fig. 1, and the bolt openings in the flange of the tread sections do not extend entirely the whole length of the flange 80 but are omitted at and adjacent its middle 85 and this is also true of the bolt openings in the flange upon the base sections.

What is claimed is:—

A compound rail comprising a base section 90 having an upstanding flange which is wedge-shaped in cross section, said flange being provided at points with bolt openings, a tread section provided with a depending bifurcated flange the inner walls of the bifurcations of which extend in inclined planes, the said bifurcated flange being provided 95 with bolt openings which aline, the bifurca-

tion in the flange of the tread section being of such dimensions as to completely receive the upstanding flange of the base section only when initial pressure has been applied upon 5 the said tread section, the bolt openings in the flange of the base and tread sections being adapted to register only after such pressure has been applied, and bolts adapted for

engagement through the openings at such time.

In testimony whereof, I affix my signature, in presence of two witnesses.

WALTER McCAFFERTY.
